UNITED STATES PATENT OFFICE.

CHARLES MADISON CROOK, OF CHICAGO, ILLINOIS, ASSIGNOR TO STROMBERG ELECTRIC COMPANY, OF CHICAGO, ILLINOIS, A CORPORATION OF MAINE.

SECONDARY-CLOCK MECHANISM.

1,280,171.

Specification of Letters Patent.

Patented Oct. 1, 1918.

Application filed April 9, 1914. Serial No. 830,690.

To all whom it may concern:

Be it known that I, CHARLES MADISON CROOK, a citizen of the United States, residing at Chicago, in the county of Cook and State of Illinois, have invented new and useful Improvements in Secondary-Clock Mechanism, of which the following is a full, clear, concise, and exact description, reference being had to the accompanying drawing, forming a part of this specification.

My invention relates to improvements in secondary clock mechanisms. In secondary clocks as heretofore known it has been found that the minute hand in its upward course very often loses one or more minutes by dropping back due to its own weight. Similarly on its downward course its weight causes it to drop forward and to gain one or more minutes. As a result, it is never possible to be sure that the clock is registering the correct time.

It is one of the principal objects of my invention to overcome these objections by locking the minute hand so that it cannot move except when properly moved forward by the clock mechanism.

It is a further object of my invention to provide suitable means for efficiently locking the escapement so that the clock hands will be moved forward the proper distance and only the proper distance and only at the proper time.

Additional objects of my invention are to provide means for easily setting the clock when necessary; to provide a secondary clock having a simple structure so arranged that all of the parts are readily accessible for the purpose of inspection, oiling or repairs; and to provide a secondary clock mechanism which is simple and efficient in its operation and economical to manufacture.

Further objects and advantages of my invention will be apparent from the following description taken in connection with the appended claims.

I have described in the following specification and illustrated in the accompanying drawings a secondary clock mechanism embodying my invention, by way of example, it being clearly understood that numerous changes may be made in the form, construction and arrangement of the parts without

departing from the spirit of my invention or exceeding the scope of the appended claims, the form of the invention herein disclosed being merely one preferred embodiment thereof.

In the drawings:

Figure 1 is a side elevation of a secondary clock mechanism constructed in accordance with my invention, showing the same secured to the door of a clock;

Fig. 2 is a detailed perspective, on a larger scale, showing part of the base;

Fig. 3 is a perspective showing the frame which carries the operating mechanism;

Fig. 4 is a similar view showing part of the operating mechanism removed from the frame;

Fig. 5 is an enlarged cross-sectional view of the device as shown in Fig. 1 removed from the door, the section being taken on the line 5—5 of Fig. 6, looking in the direction of the arrows;

Fig. 6 is a similar view taken on the line 6—6 of Fig. 5 looking in the direction of the arrows;

Fig. 7 is a similar view taken on the line 7—7 of Fig. 5, looking in the direction of the arrows;

Fig. 8 is a detailed view in cross-section taken on the line 8—8 of Fig. 5, looking in the direction of the arrows; and

Fig. 9 is a view in rear elevation reduced.

Like reference characters refer to like parts throughout the following description and the several figures of the drawings.

The embodiment of the invention illustrated comprises a secondary clock mechanism of the sort in which an electromagnet is connected to a master-clock which is arranged to cause the magnet to be energized once every minute for the purpose of rotating the hands of the clock. The clock is provided with a suitable door 10 having the usual opening 11 in which a glass 12 is held with a split ring 13 or other suitable means. The clock face 14 is mounted at the rear of this opening and is secured to the front of an upright 15 mounted on the back of the door and which not only serves as a support for the clock face, but also as a support for the driving mechanism of the clock, which mechanism is bodily mounted upon this sup-

- port 15. The operating mechanism of the clock comprises in general three parts; the base, the frame and the operating mechanism, including a pair of electromagnets.
- 5 The base 16 comprises a rectangular casting having a center opening through which the clock stem may project and is secured to the upright 15 by a plurality, preferably four, of screws which pass through the strip from 10 the front and engage in suitable screw-threaded openings at the four corners of the base. Extending rearwardly from the base, at its top and bottom, are a pair of parallel flanges 17 which form a groove for the reception of the rods 18 of the frame. There are two of these rods, one at the top and bottom of the frame, which are secured between the side plates 19 and 20, comprising a portion of the frame, by means of screws 21.
- 15 20 These rods are arranged in the grooves formed between the flanges 17 and are locked in position by means of screws 22 adapted to pass through the base, the heads of the screws being arranged to engage in a central groove on the rods and being adapted to be countersunk in bushings 23 formed on the receptive top and bottom flanges on the base.
- 25 The driving mechanism of the clock is mounted in the frame formed by the two side plates and a pair of front and back members 24. These two members are the same in construction and lie in suitable recesses formed in the edges of the two side members, being clamped in position by 30 means of rods 25 which, at their rear ends, are riveted to the back member, and, at their front end, are adapted to receive screws 26 which pass through the front member. The stem 27 of the clock, the front end of which 35 is adapted to project through the dial and receive the minute hand 28, (mounted rigidly thereon), is mounted between the front and back members and has, rotatably mounted thereon, a sleeve 29, which sleeve 40 also projects through the dial and is adapted to receive the hour hand 30. This sleeve is driven from the minute hand stem by 45 means of a reducing gear comprising a pinion 31 mounted on the stem, and adapted 50 to mesh with the gear wheel 32 mounted upon, and rotating with, a shaft 33 secured between a pair of downwardly extending lugs 34 formed on the back and front members. This shaft also carries a pinion 35 55 rigidly connected with the gear and meshing with a gear 36 mounted upon the sleeve carrying the hour hand. The reducing gear thus described operates to cause the hour hand to make one revolution while the 60 minute hand is making twelve. The minute hand stem is driven and operated from an intermittently rotating shaft 37 mounted between the two side members and carrying a worm gear 38 adapted to mesh with a pin- 65 ion 39 mounted directly upon the minute

hand stem. This worm gear not only serves as a means for driving the minute hand and the hour hand stems, but also provides a means for preventing the stems from being rotated by any other means except the worm 70 gear; in other words, this worm gear prevents any slippage on the part of the mechanism of the clock, and also prevents the weight of the hands from causing the mechanism to skip.

75 The worm gear shaft is rotated once every minute by a pawl and ratchet mechanism, operated by an electromagnet energized from the master-clock once every minute. The ratchet wheel 40 of this pawl and 80 ratchet mechanism is rigidly mounted upon the worm gear shaft and is adapted to be engaged by a pawl 41 comprising a pair of spaced-apart arms pivoted at 42 upon the end of a rocking arm 43. The forward spacing member 44 of these two arms provides the engaging member of the pawl which is adapted to engage the teeth of the ratchet wheel, and this pawl is held into engaging position with the ratchet teeth by means of 85 a coiled spring 45, one end of which is connected to the pawl and the other end of which is connected to a second backlash pawl 46, adapted to engage the ratchet teeth 90 of the wheel on its under side to prevent 95 backlash of the ratchet wheel. This pawl is pivoted to one side of the frame as illustrated.

95 The rocking arm 43 is provided, at its bottom, with a rearwardly extending arm 47 and the two arms, in effect, provide a bell crank lever being mounted upon a cross bar 48 secured between the two side members of the frame. The pivotal mounting of this bell crank lever is about central of the lower 100 laterally extending arm 47, so that the arm will have a free rocking movement. At the pivotal point the arm is rigidly secured to a sleeve surrounding the rod 48 and on the opposite end of the sleeve is a second arm 105 49, the two ends of the arms being connected by a member 50 riveted at its outer ends to the two arms and having riveted thereto, so that it is supported in the upper side of the two arms, an armature 51 of an electromagnet, 110 which armature, on its upper side, is provided with a thin layer 52 of non-conducting material, such as brass, for preventing the armature from sticking to the ends of the pole pieces of the electromagnet. The 115 armature lies in a position between a pair of rearwardly extending arms 53 of the side plates and the bottom of the electromagnet, which electromagnet comprises a pair of independently mounted spools of wire 54, 55 120 suitably wound on iron cores. The cores of each of the magnets are supported in position from a cross member 56 secured upon a pair of rearwardly extending arms 57 of 125 the side plates of the frame, by means of 130

screws 58 which pass through the cross member, through an iron bridging member 59, against which bridging member the pole pieces are clamped by the screws, and into the 5 pole pieces. The iron bridging member 59 forms, not only a means against which the spools are securely fastened by the screws, but also a means for magnetically connecting the two pole pieces at their top to complete 10 the path for the magnet flux when the armature is attracted by the electromagnet. The electromagnet attracts its armature once every minute, and, in attracting its armature, the arm 43 is caused to rock outwardly, thus placing under tension a coiled spring 60, one end of which is secured to a pin 61 projecting from the side of the frame. The other end of the spring is secured to a pin 62 extending laterally from the lower 20 end of the rocking arm 43 and passing through a suitable opening in the side frame.

When the electromagnet is deenergized the coiled spring 60 causes the rocking arm 43 to make a return movement so as to rotate the ratchet one notch, thereby operating the clock and moving the minute hand one minute. A post 63 on one of the side plates of the frame serves as a stop to limit the outward movement of the rocking arm 43 and a similar stop 64 limits its return stroke. Consequently its effective stroke is just sufficient to rotate the ratchet the proper distance to cause the minute hand to be advanced one 35 minute.

Means are provided also for preventing any movement of the ratchet other than its proper advance movement, as above described. When the arm 43 reaches the limit 40 of its return or operating movement it engages the stop 64 and becomes wedged between this stop and the ratchet, whereby further rotation of the ratchet in a forward direction is prevented. As backlash is prevented by the spring pressed pawl 46, the ratchet is effectually locked against rotation in either direction except during the interval it is being driven forward by the operating 45 pawl.

50 When it is necessary to set the clock, the hour hand is manually rotated about its sleeve to its correct position and the minute hand is advanced by means of a small wire handle 65 secured to the arm 43; a pull on the handle rocking the arm in the same manner as when caused by the influence of the magnet.

It will be noted, by the above construction, first, that the clock mechanism, including 55 the base and the operating parts, constitutes a unitary device which, in itself, may be readily mounted upon a supporting member. It will also be noted that the frame which is secured to the base, and on which all of the 60 operating parts of the clock are mounted,

also comprises a unitary structure which may be disconnected and removed from the base without removing the base, if so desired. It will also be noted that the driving gear and the operating pawl and ratchet 70 mechanism are mounted between the base and the electromagnet, the electromagnet being mounted at the rear of the frame and the two spools being readily removable from the frame independently of one another to 75 permit access to the mechanism of the clock for the purpose of oiling, repair, etc. It will also be noted that it is not even necessary to remove both magnets for access to the driving trains, etc., as each magnet is removable 80 independently of the other, and, therefore, only one magnet need be removed if access is only desired at one side of the clock. The whole mechanism is simple, readily assembled and disassembled, and, at the same time, 85 provides an efficient secondary clock mechanism having means for positively locking the hands thereof against movement except the movement imparted thereto by the electromagnet and its associate parts. 90

Having disclosed my invention what I claim as new and desire to secure by Letters Patent, is:

1. In a secondary clock, a member having a dial opening therein, a supporting bar extending across said opening, a base detachably secured thereto, a frame detachably secured to said base, a clock hand, a shaft on which said hand is secured, supported by said frame, and electromagnetic actuating 95 mechanism for rotating said shaft also carried by said frame, said frame having horizontal rods lying in a plane substantially parallel to the plane of said first member and said base having recesses to receive said 100 rods.

2. The combination with a frame comprising a pair of spaced apart side members having rearwardly extending arms at the top, clock hand operating mechanism within said 110 frame between said side members, electromagnets for operating said mechanism supported from said arms behind said mechanism, and an armature at the bottom of the frame. 115

3. The combination with a face plate having top and bottom grooves in the rear face thereof, of a clock operating mechanism frame having a pair of cross rods adapted to fit in said grooves, and locking means for 120 locking the cross rods in said grooves.

4. The combination with a frame comprising a pair of spaced apart side plates having rearwardly extending arms at the top, clock mechanism supported within said frame, a driving ratchet wheel supported within the frame near one of the side pieces, a bell crank lever mounted in the lower end of said frame and having one arm extending upwardly along one of said side pieces and con- 125 130

rying at its end a pawl for operating the ratchet wheel, the opposite arm extending substantially horizontally and carrying an armature, and an electromagnet supported at its upper end from said rearwardly extending arms and having the ends of its cores in close proximity to the armature.

In witness whereof, I have hereunto subscribed my name in the presence of two witnesses.

CHARLES MADISON CROOK.
